CLAIM

The ornamental design for a texture pattern cookie sheet, as shown and described.

DESCRIPTION

FIG. 1 is a front, right, top perspective view of a texture pattern cookie sheet, showing my new design;
FIG. 2 is a rear, left, bottom perspective view thereof;
FIG. 3 is a front elevational view thereof;
FIG. 4 is a rear elevational view thereof;
FIG. 5 is a left side view of the enlarged scale thereof;
FIG. 6 is a right side view of the enlarged scale thereof;
FIG. 7 is a top plan view thereof;
FIG. 8 is a bottom plan view thereof;
FIG. 9 is an enlarged view of detail 9 in FIG. 1;
FIG. 10 is an enlarged view of detail 10 in FIG. 1;
FIG. 11 is an enlarged view of detail 11 in FIG. 2;
FIG. 12 is an enlarged view of detail 12 in FIG. 2;
FIG. 13 is an enlarged view of detail 13 in FIG. 3;
FIG. 14 is a sectional view of 14-14 along the line in FIG. 3;

FIG. 15 is an enlarged view of detail 15 in FIG. 7;
FIG. 16 is an enlarged view of detail 16 in FIG. 8; and,
FIG. 17 is an enlarged view of detail 17 in FIG. 14.
The dashed broken lines in the figures illustrate portions of the texture pattern cookie sheet which form no part of the claimed design.

The dash-dot-dash broken lines are for notating enlarged views and form no part of the claimed design.

1 Claim, 16 Drawing Sheets
